UNITED STATES PATENT OFFICE.

FITZPATRICK EASSIE, OF RATHFARNHAM, IRELAND.

SADDLE PANEL.

Application filed February 17, 1927, Serial No. 168,884, and in Great Britain November 28, 1925.

This invention relates to saddle panels, and its principal object is to replace the ordinary panel which is permanently secured to the saddle, by a separate panel adapted 5 to be retained in position by means of its engagement with the girth strap, this strap being the sole means employed for connecting the panel with the saddle. The back of the saddled animal will be thereby relieved from a considerable amount of friction which when a panel according to this invention is used will take place between the saddle and the panel. Other objects and 10 advantages of the invention will be apparent from the following description and drawings.

Figures 1 and 2 represent in perspective two examples of saddle panels embodying this invention.

20 The panel comprises a leather cover A and a lining B of felt or other suitable relatively soft material, the latter being, say, half an inch thick, both cover and lining being cut out at C to leave an opening to come over 25 the spine of the animal. The saddle tree (not shown) lined only with thin felt or leather, can rest on the top of this panel when in position. At each side of the panel is secured a buckle D, which when the saddle 30 is in position can engage the topmost hole of the first girth strap of the saddle. Between the leather and the felt are concealed stiffeners E comprising a number of sections, each about an inch across, of three- 35 ply wood or other material of similar strength and lightness, which stiffen the panel without materially reducing its pliability, and prevent the saddle from embedding itself in the panel and reducing the 40 effectiveness of the felt as a padding at the parts where pressure is greatest. These stiffeners are arranged in a reverted curve with a downwardly directed cusp as illustrated, and the divisions between the sections are so arranged that the sections lie 45 across the direction of the thrust of the saddle tree, being approximately horizontal at the front where they come under the fore arch of the saddle and thereafter tending to 50 occupy a more or less vertical position.

In the panel represented in Figure 1, the leather is hollowed out at F to avoid excessive projection of the buckle exposing the felt, to which the strap G of the buckle is 55 stitched. The stiffeners E may be glued to

a piece of canvas and attached to the leather by rivets at intervals.

In the panel represented in Figure 2, the strap G of the buckle D is secured to the leather, and a square piece of the leather 60 is cut out at H, leaving a recess in which the buckle can nestle against the felt. Each section of the stiffener E is individually riveted to the leather.

Although I have herein described and illustrated two practical examples of saddle panels embodying this invention, it will be understood that many variations may be made in the shape and construction of the panel without departing from the principles of the invention, the scope of which is 65 defined in the following claims.

What I claim and desire to secure by Letters Patent of the United States is:—

1. In a saddle panel, a leather cover, a 75 lining of relatively soft material such as felt, stiffeners divided into small sections secured between said cover and said lining, and means for engaging the panel with a girth strap of a saddle.

2. In a saddle panel, a leather cover, a lining of relatively soft material such as 80 felt, stiffeners divided into small sections secured between said cover and said lining, said sections being so disposed as to lie 85 across the direction of the thrust of the saddle tree in use, and means for engaging the panel with a girth strap of a saddle.

3. In a saddle panel, a leather cover, a lining of relatively soft material such as 90 felt, stiffeners secured between said cover and said lining in the form of a reverted curve having a downwardly directed cusp, and means for engaging the panel with a girth strap of a saddle.

4. In a saddle panel, a leather cover, a lining of relatively soft material such as 95 felt, stiffeners of three-ply wood located between said cover and said lining and secured to said cover, and means for engaging the 100 panel with a girth strap of a saddle.

5. In a saddle panel, a leather cover, a lining of relatively soft material such as felt, and a buckle secured to the panel and adapted to engage a girth strap of a saddle, 105 said cover being cut away to form a recess to house said buckle.

6. In a saddle panel, a leather cover, a lining of relatively soft material such as 110 felt, both said cover and said lining being

cut out at the top of the panel to leave an opening adapted to come over the spine of a saddled animal when the panel is in use, stiffeners divided into small sections located 5 between said cover and said lining and secured to said cover, and means for engaging the panel with a girth strap of a saddle.

7. In a saddle panel, a leather cover, a

lining of relatively soft material such as 10 felt, stiffeners divided into small sections located between said cover and said lining and secured to said cover, and a buckle secured to the panel and adapted to engage a girth strap of a saddle, said cover being cut away to form a recess to house said buckle.
